United States Patent Office

Des. 180,765
Patented Aug. 13, 1957

180,765

SLIDE FILE

Theodore S. Briskin, Chicago, and Robert L. Moore, La
Grange Highlands, Ill., assignors to Revere Camera
Company, Chicago, Ill., a corporation of Delaware

Application May 25, 1955, Serial No. 36,195

Term of patent 14 years

(Cl. D61—1)

FIG. 1

FIG. 2

FIG. 3

FIG. 5

FIG. 4

Fig. 1 is a plan view of a slide file showing our new design;

Fig. 2 is a bottom view thereof;

Fig. 3 is a side elevation view thereof;

Fig. 4 is an end view thereof showing the right end; and

Fig. 5 is a vertical section taken along line 5—5 of Fig. 3 showing the shape of the partitions.

We claim:

The ornamental design for a slide file, as shown.
